Patented July 27, 1926.

UNITED STATES PATENT OFFICE.

PETER FRANTZ, OF STERLING, ILLINOIS, ASSIGNOR TO FRANTZ MANUFACTURING COMPANY, OF STERLING, ILLINOIS, A CORPORATION OF ILLINOIS.

DOOR-HANGER CONSTRUCTION.

Application filed January 16, 1925. Serial No. 2,768.

This invention relates to door hangers in general, but more particularly to those employed on garage doors, and more especially to those which are used on garage doors comprising a plurality of door sections which are hinged together.

Generally stated, the object of the invention is to provide a novel and improved door-hanger construction involving a plurality of vertical axes of motion for the door, so that the door may open and close in the desired manner, and having a spring device which will assist in properly closing the door.

It is also an object to provide certain features and details of construction, and combinations tending to increase the general efficiency and the desirability of a door-hanger construction of this particular character.

To the foregoing and other useful ends, the invention consists in the matters herein-after set forth and claimed, and shown in the accompanying drawings, in which,—

Fig. 1 is a front elevation of a garage door having a hanger constructed in accordance with the invention, it being understood that this view shows the inside of the door and the adjacent portions of the garage or other building.

Fig. 2 is a horizontal section on line 2—2 in Fig. 1.

Fig. 3 is an enlarged front elevation of the hanger and the adjacent portions of the door and building and track upon which the hanger travels.

Fig. 4 is a vertical section on line 4—4 in Fig. 3.

Fig. 5 is a horizontal section on line 5—5 in Fig. 3.

Fig. 6 is a view similar to Fig. 3, but on a smaller scale, and with the hanger reversed for a right-hand door, instead of the left-hand door as shown in the other figures.

Fig. 7 is a detail, horizontal section on line 7—7 in Fig. 3.

As thus illustrated, referring to Figs. 1 to 5, inclusive, the door construction may comprise sections 1 and 2 hinged together at 3, and hinges 4 for the section 2, mounted on the door frame 5 at the left of the doorway, the door thus opening to the left, as shown in Fig. 2 of the drawings.

The hanger construction comprises a bracket plate or strap 6 secured to the door section 1 by bolts 7 or any suitable means.

An inverted L-shaped rod 8 has its horizontal arm 9 pivoted at 10 on the hanger body 11, which latter is of any suitable character and is supported by the wheels 12, which travel on the track 13 in the usual or any suitable manner. With the hanger rod pivoted at 10, in the manner shown, this arm can swing about the vertical axis 10, when the door is opened and closed, in a manner that will be readily understood. In addition, the rod 8 has its vertical portion 14 suitably screw-threaded for engagement with the nuts 15 which bear against the lower edge of the strap or bracket plate 6 previously mentioned, this plate having cylindrical portions 16 that form bearings in which the vertical portion of the rod is free to turn. The rod 8 has its vertical portion provided with a laterally-projecting pin 17, and the cylindrical portions 16 are formed with a gap 18, as shown in Fig. 7, through which this pin will pass when the rod is inserted in the bracket plate. In the space between the two portions 16, there is a sleeve 19 having a longitudinal slot 20 for the pin 17, and having one end provided with laterally-extending teeth 21 forming notches between them for the end portion 22 of the coil spring 23 which is mounted on said sleeve. The other end portion 24 of this coil spring bears against the face of the plate 6 in the manner shown, and the spring is tensioned by manipulating the parts to transfer the end portion 22 of the spring from one notch to another between the teeth 21 previously mentioned, whereby the spring can be given more or less tension. Thus the weight of the door is on the nuts 15, and is communicated through the inverted L-shaped rod 8 to the pivot 10 on the body of the hanger, and consequently there are two axes of motion for the door, one axis being formed by the pivot 10 and the other axis being formed by the swivel formed by the vertical portion 14 of the hanger rod and the bearing 16 in which this vertical portion is free to turn or oscillate.

With the construction shown and described, the folding door sections may be opened in the manner illustrated in Fig. 2. At such time the hanger rod 8 swings about the pivot 10, in opposition to the tension of the spring 23, in a manner that will be readily understood. When the door is closed, the tension of the spring 23 tends to swing

- the rod 8 around into the position shown in Figs. 1, 3 and 4 of the drawings, and this tends to close the door, so that the action of the spring contributes to the closing movement of the door. The hanger construction permits the folding door sections to be swung back against the building at the side of the doorway, so that the two door sections will be substantially parallel with the track 13, if this is desired. At such time the spring 23 exerts its tension to hold the doors in this open position; but when the door sections are started in the direction of their closing movement, and as soon as they have swung around far enough, the tension of the spring is then exerted in a manner tending to straighten out the door by bringing the two sections thereof into the same plane.
- 20 The hanger construction is reversible for either a right or left door. As shown in Figs. 1 to 5, the hanger is applied to a left-hand door; but as shown in Fig. 6 is applied to a right-hand door,—that is to say, the door which swings around opens to the right. As shown in Fig. 6, the bracket plate or strap 6 has been taken off from the hanger rod and turned upside down so that it projects to the right instead of to the left, thus turning the spring 23 upside down, as well as the sleeve 19, so that the spring in this position will function to assist in closing the door to the left. Under such circumstances, the hanger rod 8 is reversed also, on its pivot 10, and normally extends to the left from this pivot, the hanger body 11 being formed to receive the horizontal portion 9 of the rod in either position thereof. Thus the reversibility of the hanger, for either a right or left door, involves merely the taking off of the nuts 15 and the turning of the plate 6 and the spring and sleeve end for end, or upside down, so as to reverse the action of the spring for either a right or left door.
- 50 Thus, in its normal position, the arm 9 or upper portion of the rod 8 is in the vertical plane of the track 13 upon which, and within the housing of which, the hanger travels.
- 55 When the arm 9 is in this position, the door is necessarily fully closed, and the vertical edge of the section 1 is held properly in place, so that the closing movement of this vertical edge of the door is accurate and calculated to bring the door into engagement with any sort of holding or fastening means (not shown) employed for this purpose. Without the spring, for example, the door might not fully close, and might stop its closing movement with the arm 9 not quite fully in the position in which it is shown in Figs. 3 and 4, so that there would be danger of improper closing action; but, with the provision of the spring 23, or any

suitable spring for this purpose, tending to force the arm 9 into its normal position in the vertical plane of the track, the vertical edge portion of the section 1 will be more certain to be brought into proper closing position each time the door is closed. 70

Without disclaiming anything, and without prejudice to any novelty disclosed, what I claim as my invention is:

1. The combination of a door, a track, a hanger on the track, a thrust bearing to pivotally support the door on the hanger, and a spring applied to said hanger above said bearing and acting to assist in the closing of the door, said bearing and the door being detachable from the hanger without compression of said spring, and the connection thus formed between the door and the hanger being adjustable for right and left doors, said hanger comprising an inverted L-shaped hanger-rod pivoted on the hanger body and swiveled on the door, a projection on the vertical portion of the rod, and a sleeve mounted on the vertical portion of the rod and slotted to receive said projection, one end of said sleeve being provided with a plurality of notches, said spring being a coil spring mounted on said sleeve, one end of said spring being displaceable from one notch to another to tension the spring, and means to engage the other end of the spring. 80 85 90 95

2. The combination of a door, a track, a hanger on the track, a thrust bearing to pivotally support the door on the hanger, and a spring applied to said hanger above said bearing and acting to assist in the closing of the door, said bearing and the door being detachable from the hanger without compression of said spring, and the connection thus formed between the door and the hanger being adjustable for right and left doors, said hanger comprising an inverted L-shaped hanger-rod pivoted on the hanger body and swiveled on the door, a projection on the vertical portion of the rod, and a sleeve mounted on the vertical portion of the rod and slotted to receive said projection, one end of said sleeve being provided with a plurality of notches, said spring being a coil spring mounted on said sleeve, one end of said spring being displaceable from one notch to another to tension the spring, and means to engage the other end of the spring. 100 105 110

115 120 125

11. In a door hanger, a bracket plate adapt-

130

130

ed to be secured to the door, an inverted L-shaped hanger-rod having swivel engagement with said bracket plate, a nut on said rod to engage the plate and carry the weight 5 of the door, a wheeled hanger body to support the hanger on a track, and a coil spring applied to said swivel above said nut and exerting its tension to normally keep the upper portion of said rod in the vertical 10 plane of said track, so that by removal of the nut the plate and spring can then be slipped off the rod, without the necessity of compressing said spring, and the connection thus formed between the door and the 15 hanger being adjustable for right and left doors, said spring having a sleeve on said rod, one end of said spring being adjustably engageable with one end of said sleeve, thereby to change the tension of the spring.

20 4. The combination of a door, a track, a hanger to support the door on the track, and a spring applied to said hanger and acting to assist in the closing of the door, said hanger comprising an inverted L-shaped 25 hanger-rod pivoted on the hanger body and swiveled on the door, a projection on the vertical portion of the rod, and a sleeve mounted on the vertical portion of the rod and slotted to receive said projection, one 30 end of said sleeve being provided with a plurality of notches, said spring being a coil spring mounted on said sleeve, one end of said spring being displaceable from one notch to another to tension the spring, and 35 means to engage the other end of the spring.

5. The combination of a door, a track, a hanger to support the door on the track, and a spring applied to said hanger and

acting to assist in the closing of the door, said hanger comprising an inverted L-shaped 40 hanger-rod pivoted on the hanger body and swiveled on the door, a projection on the vertical portion of the rod, and a sleeve mounted on the vertical portion of the rod and slotted to receive said projection, one 45 end of said sleeve being provided with a plurality of notches, said spring being a coil spring mounted on said sleeve, one end of said spring being displaceable from one notch to another to tension the spring, and 50 means to engage the other end of the spring, there being a plate secured to the door and forming swivel bearings above and below said sleeve, with gaps in said swivel bearings through which said projection can pass 55 to permit insertion of the rod through said bearings, said plate and spring and sleeve being removable bodily from the rod, and being reversible by turning them upside down for either a right or left door.

6. In a door hanger, a bracket plate adapted to be secured to the door, an inverted L-shaped hanger-rod having swivel engagement with said bracket plate, a wheeled 60 hanger body to support the hanger on a track, and a coil spring applied to said swivel and exerting its tension to normally keep the upper portion of said rod in the vertical 65 plane of said track, a sleeve on said rod, one end of said spring being adjustably engageable with one end of said sleeve, thereby to change the tension of the spring.

Specification signed this 12 day of January, 1925.
